UNITED STATES PATENT OFFICE.

FRANK T. WHEELER, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

LATCH FOR ELECTRIC-SWITCH BOXES.

Application filed September 23, 1925. Serial No. 58,049.

My invention relates particularly to a latch and fastening device for holding the cover closed.

The main object is to provide a simple and inexpensive construction by which the cover will be automatically latched when closed and which can be readily sealed.

In the preferred form of construction, the latch is formed of a strip of metal having lugs struck out from the edges of the strip and bent at an angle so as to provide cam-like shoulders and abrupt latching edges. The cover is provided with a loop or strap adjacent the latch so that a seal or wire may be used to connect the latch and cover loop and prevent unauthorized opening.

Fig. 1 is a perspective view of an electric switch-box embodying the improvements of my invention.

Fig. 2 is a fragmentary transverse sectional view showing a latch with a seal attached.

Fig. 3 is a vertical sectional view and side elevation showing the cover and box interlocked or latched.

Fig. 4 is a perspective view showing the novel features of the cover and latch separated.

Fig. 5 is a transverse sectional view showing the cover partially closed.

The box is usually formed of sheet steel or iron and has a body 6 and a cover 7. These parts are preferably connected together by hinges 8-8. Any form of switch mechanism may be employed but since it is not involved in this invention, none is illustrated. Such switch constructions are usually provided with suitable operating handles, such as 9.

The latch member 10 is preferably formed of resilient metal or spring steel having its inner end riveted or welded at 11 to the body of the box. The outer end of the latch is provided with one or more inclined angular lugs 12-12 adapted to interlock with one edge of the cover adjacent the opening 13, for instance, at the ends 14 of the loop strap 15. These lugs are preferably formed by cutting or stamping portions from the edges of the latch strip. The loop 15 is preferably formed by cutting the metal and drawing or sketching the strap thus formed.

The end of the latch 10 is provided with

an opening 16 which is adapted to be in alignment with the passage beneath the loop 15 when the cover is closed.

The latch may also be provided with an opening 17 adapted to receive a padlock (not shown) or a wire 18 of the seal 19. This wire is also adapted to pass through the opening 16 so that the wire may conveniently encircle the loop 15 and connect the loop and latch securely together when desired.

When the cover is being closed, as shown in Fig. 5, the cover slides over the outer inclined faces of the lugs 12-12 and forces the latch toward the wall of the box 6 until the tips of the lugs 12 snap out over the opposite ends of the loop strap 15. The lower edges of these projections 12 are also preferably inclined so as to more securely hold the parts together.

The cover can be readily opened by simply retracting the latch by hand.

A particular advantage of this construction is that the integral sealing loop 15 may be provided at practically no expense and, further, it provides a means whereby a sealing wire may be passed through the openings in the spring arm and in the loop in such a manner as to completely enclose the loop and a portion of the arm. Obviously this prevents any manipulation of the seal or wire so as to even partially open the box without destroying the seal.

One particular advantage of the spring arm 10 is that, in this construction, a thin resilient spring may be used and the cam lugs 12 may be formed by a simple shearing operation at the edges of the strip of stock as it passes through the dies. The angle of these lugs causes the spring arm to yield easily to the closing movement of the cover and the lugs are also angled laterally so that the wear upon the edges of the cooperating hole in the cover is not confined to the width of the thickness of the metal of the arm but it is spread out to a comparatively considerable width.

I claim:

1. A latch for a switch box having a cover hinged thereto, said cover having an opening near one edge, a spring arm carried by the box and having one end adapted to pass through said opening, the opposite outside edges of said end having inwardly bent in-

clined catches adapted to cause said arm to be tensioned as the cover is closed and to snap into engagement with the cover at the edge of said opening.

5. 2. A latch for a switch box having a cover hinged thereto, said cover having an opening near one edge, a spring arm secured to the box and having a free end adapted to pass through said opening, the opposite edges of said end having inwardly bent inclined catches adapted to cause said arm to be tensioned as the cover is closed and to snap into engagement with the cover at one edge of said opening, said cover having an integral outstanding loop at one edge of said opening adapted to receive a sealing wire said inclined catches engaging the cover at the opposite ends of said loop.
- 10 15

3. A latch for a switch box having a cover,

said cover having an opening, a spring arm 20 secured to said box and adapted to enter said opening as the cover is closed, said arm having an opening and beveled catches at opposite sides thereof and said cover having a loop integral therewith and in line 23 with said opening when the cover is closed.

4. A latch for a switch box having a cover, said cover having an integral loop and an opening adjacent thereto, a spring arm carried by the box and having a free end adapted to pass through said opening, said end having inwardly bent inclined catches at its opposite outside edges adapted to cause said arm to be tensioned as the cover is being closed and to snap into engagement with the edge of the opening in the cover when the cover is fully closed.

FRANK T. WHEELER.
